(57) **CLAIM**

The ornamental design for a bottle, as shown and described.

DESCRIPTION

FIG. 1 is a top, front, left side perspective view of a bottle showing our new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and

FIG. 7 is a bottom plan view thereof; and,

FIG. 8 is a bottom, front, left side perspective view.

The broken lines immediately adjacent to the shaded area represent unclaimed boundaries of the claimed design.

The remaining broken lines shown in the drawings are included for the purpose of illustrating environmental structure and form no part of the claimed design.

The oblique shade lines shown in drawing FIGS. 1-7 of the claimed design represent transparency of the surfaces.
